(57) CLAIM

The ornamental design for a footwear for temporary use, as shown and described.

DESCRIPTION

FIG. 1 is a perspective view of a footwear for temporary use showing my new design;

FIG. 2 is a right side elevation view thereof;

FIG. 3 is a left side elevation view thereof;

FIG. 4 is a front view thereof;

FIG. 5 is a rear view thereof;

FIG. 6 is a top view thereof; and,

FIG. 7 is a bottom view thereof.

The broken lines shown in the drawings represent portions of the footwear for temporary use that form no part of the claimed design.
